TAPING HEAD FOR WINDING APPARATUS

Herman Zarafu, New York, N. Y., assignor to
Elevator Supplies Company, Incorporated,
Hoboken, N. J., a corporation of New Jersey

Application March 1, 1937, Serial No. 128,399

7 Claims. (Cl. 117—41)

This invention relates to apparatus for winding tape or the like on cables or the like, and particularly to the taping heads thereof, and provides improvements therein.

The present invention provides an apparatus of the character described in which tapes of different width may be applied smoothly, in either a lap wrap or a butt wrap, without buckling, and under tension. It provides a taping head readily adjustable for tapes and tape-packages of different width, and for the positioning of the center or mid-planes of tape packages of different width in one or the same position, that is, so that the mid-planes of tape packages of different width all lie in the mid-plane of the package holder.

The invention further provides a taping head adaptable for the use of large diameter tape packages and for the holding of the tape-package in the package holder without slipping.

The invention further provides for the quick replenishment of tape packages when the tape remaining in the package has run low or run out.

An embodiment of the illustration is illustrated in the accompanying drawings, wherein:

Fig. 1 is a view mainly in cross-section of one of the taping heads;

Fig. 2 is a diagrammatic view illustrating a pair of taping heads mounted on a rotating frame or "flyer", and showing the application of a pair of tapes to a cable.

Fig. 3 is an end view of the hub of the package holder, looking from the right, Fig. 1.

Fig. 4 is a top plan view of the outer end of said hub, and showing in section the outer plate of the package holder.

Figs. 5 and 6 are each views in side elevation of parts of the package holder.

Fig. 7 is a diagrammatic view illustrating the position of lugs 62 of the outer plate 15 at different stages during the removal of the plate from the hub, such as occurs when the package support is to be replenished.

Referring to said drawings, numeral 10 designates the taping head. The taping head comprises a tape-package support 12 comprising oppositely arranged plates 14, and 15, a hub 18 and a spindle 20. The taping head further comprises a tape tensioning device 24 comprising a brake 22 and a tension lever 26 having an arm 28 thereon over which the tape runs. The tension lever 26 operates against the force of a spring 30. The tension-lever 26 also operates on the brake 22 through an arm 32 thereon, to which arm 32 one end of a brake-band 34 is attached. The construction and operation of the

tension lever 26, spring 30 and brake 22, is such as to effect the paying-off of the tape *t* from the tape package T under a substantially uniform winding tension. The operation of similar parts in effecting the paying-off of tape from a package in a tape winding machine, under substantially uniform tension, is more fully described in the patent to Smith and Zarafu #1,937,918, granted December 5, 1933. Briefly described, the operation is as follows: The spring 30 acts on the tension arm 26, with an initial tension, say ten pounds. When the winding of the tape begins the tape (in the form of a loop) must pull upon the tension arm with a force of at least five pounds (in the concrete case assumed), before the spring 30 begins to flex. As the tension arm 26 moves against the tension of the spring 30, the arm 32 thereon (to which one end of the brake band 34 is connected) moves in the direction to relax the action of the brake 22 on the package support 12, and thereby enables the tape to run off with slightly less tension, counteracting the increase of tension thereon due to the increase of tension of the spring 30 by the movement of the tension lever 26 just referred to. As the tension on the tape *t* is relieved by the action of the brake 22, the tension lever 26 will be moved back by the spring 30 to a position corresponding with the slightly decreased tension of the said spring 30. By the same movement of the tension arm 26 which relaxes the tension thereon of the spring 30, the action of the brake 22 is slightly increased through the arm 32. By these counterbalancing actions of the brake 22 and of spring 30, a substantially constant tension is maintained on the tape paying-off from the package in the package holder 12.

One or more taping heads 10 are mounted on a frame or "flyer" F which is rotated around the axis of a cable or the like C in the process of winding the tapes *t* onto said cable C.

Wrapping guides G, mounted on the flyer F apply the tapes *t* to the cable C. Advantageously these wrapping guides have crowned rollers thereon, and the tapes *t* are led to the wrapping guides G in such manner that the center line of the tape, irrespective of the width of the tape runs onto the apex of the crowned roller. Guides 40, 41 are mounted on the flyer F, and the tape *t*, as it unwinds from the tape package T, reeves over the guide 40, then in a loop over the arm 28 on the tension lever 26, then over the guide 41 to the winding guide G and from thence onto the cable C.

The spindle 20 of the package support 12 turns

- in bearings 44 mounted on a part of the flyer F, and as the flyer turns, the package support 12 and spindle 20 turn to pay-off tape from the tape package T as tape is wound onto the cable C.
- 5 The turning of the package support 12 and spindle 20 is against the frictional resistance of the brake 22 regulated by the action thereon of the tension lever 26 and spring 30, as hereinbefore described.
- 10 According to the present invention the taping heads are so constructed and arranged that the mid-planes of tape packages T of different width lie in the mid-plane of the package holder, designated by the line M—P, Fig. 1, and the arrangement of the guides 40, 41, arm 28 and winding guide G is such that the center lines of tapes t of different width run over the said parts, at the same points. The effect of such construction and arrangement is that tapes of different 15 width may be applied smoothly in either a lap wrap or a butt wrap without buckling, and under tension.
- 15 To this end the plates are provided with a means 50 for positioning the plates 14 and 15 so as to position and hold the tape packages T of different width with the mid-planes thereof in the mid-plane M—P of the support 12. The means 50 for positioning and holding the plates 14, 15 as aforesaid may, as here shown comprise 20 a pair of nuts 53, 54 arranged within the hub 18 and engaging an oppositely threaded screw 56. Suitable connections are provided between the nuts 53, 54 and plates 14, 15. To provide for the replenishment of tape packages in the holder 12, 25 the connection between the outside plate 15 and the nut 54 at the outer end of the hub, is a detachable one. As here shown the inner plate 14 is connected to the nut 53 by means of one or more lugs 58, which latter pass through a longitudinal slot or slots 59 to the inner side of the hub.

30 The detachable connection between the outer plate 15 and the nut 54 may comprise one or more lugs 62 projecting from the plate 15 through a slot or slots 64 in the outer end of the hub into a position to be engaged by the nut 54. As here shown, the lugs 62 may be provided on a ring 66 which is fastened to the plate 15 by screws or the like as indicated at 68, Figs. 1 and 4. Each slot 64 has an offset portion 64^a running through the end of the hub 18. Nut 54 is provided with one or more slots 70 each of which is in alignment with the offset portion 64^a of a slot 64. The nut 54 may be prevented from 45 turning by means of a slot 74 therein and a key or rib 76 running longitudinally along the inside of the hub 18.

50 Any suitable means may be provided for turning the oppositely threaded screw 56. As here shown the turning means comprises a cap 80, attached to the outer end of the screw 56, and having a nut 82 thereon which may be engaged by a wrench for turning the said screw 56.

55 The hub may be provided with transverse fins 85 for engaging and holding a tape package against rotation on the hub. As the moment between the tape and the hub, when the tape pays off from the circumference of a tape package of considerable diameter, is large, and as 60 the tension is also relatively large, it is advantageous to provide means in addition to the fins 35 for preventing rotation of the tape package T on the hub 18. The holding action of the fins 85 may be amplified by turning the screw 56 so as to force the plates 14, 15 into clamping

65 engagement with the sides of the tape package T, and for better effecting the clamping action, the inner faces of the plates 14 and 15 may be provided with a plurality of radial ribs 88.

70 The action of the oppositely threaded screw 56 and the nuts 54 is to move the plates 14, 15 symmetrically toward the mid-plane M—P. Consequently tape packages of different width will be supported and held in the package support 12 with the mid-plane packages all lying in the mid-plane M—P of the package support.

75 To replenish the taping head, the oppositely threaded screw 56 is turned to bring the nut 54 to a position where the lugs 62 on the outer plate 15 may enter the offset portion 64^a of the 15 slot 64. The nut 54 is shown in the position just described in Fig. 4. The plate 15 and the lugs 62 thereon are then slid longitudinally from a position a Fig. 7 to position b Fig. 7, then rotated from position b to the position c in the offset portion 64^a of the slot, and then slid off of the hub through slot 64^a, as indicated at positions d and e, Fig. 7. The spent tape package is then removed, and a new package placed onto the hub. Plate 15 is then replaced on the hub and brought to a position where it will again be engaged by the nut 54 by the reverse of the movements just described with reference to Fig. 7. When the plate is in position and the lugs 62 thereon are in the portion of the slot 64 beyond 30 the offset portion, the oppositely threaded screw 56 is turned in a position to move the plates 14, 15 toward the mid-plane M—P and thereby position and hold the replenishing tape package T in the support 12 with its mid-plane in the 35 mid-plane M—P of the support 12.

40 The invention may receive other embodiments than that herein specifically illustrated and described.

What is claimed is:

1. A taping head of an apparatus for winding tape or the like on cables or the like comprising a rotatable tape-package support, and tension-regulating means for acting on said package support to allow the tape to pay off from the package under tension, and means on said support adjustable with respect to the transverse mid-plane thereof, for positioning and holding tape-packages of different width with the mid-planes thereof in the transverse mid-plane of said support. 45

2. A taping head of an apparatus for winding tape or the like on cables or the like comprising a rotatable tape-package support, and tension-regulating means for acting on said package support to allow the tape to pay off from the package under tension, and means on said support adjustable with respect to the transverse mid-plane thereof, for positioning and holding tape-packages of different width with the mid-planes thereof in the transverse mid-plane of said support, said package support comprising a hub, a pair of plates and means for moving said plates in opposite directions to positions symmetrically spaced from the transverse mid-plane of said support. 55

3. A taping head according to claim 2, further comprising a detachable connection between the plate at the outer side of the support and said moving means. 60

4. A taping head of an apparatus for winding tape or the like on cables or the like comprising a rotatable tape-package support, and tension-regulating means for acting on said package support to allow the tape to pay off from the 65

package under tension, and means on said support adjustable with respect to the transverse mid-plane thereof, for positioning and holding tape-packages of different width with the mid-planes thereof in the transverse mid-plane of said support, said package support comprising a hub, a pair of plates, a pair of nuts, a connection between each plate and each nut, and an oppositely threaded screw engaging said nuts for moving the plates through said connections in opposite directions to positions symmetrically spaced from the transverse mid-plane of said support.

5. A taping head according to claim 4, wherein said nut at the outer end of the hub has a slot therein and said hub at said outer end has a longitudinal slot therein having an offset portion, and wherein the connection of the outer plate to its nut comprises a lug projecting through 10 said hub slot into said hub, said outer-plate be-

ing detachable by movement of said outer nut to a position where said lug can reach the offset portion of the hub-slot, and then giving said plate a longitudinal movement and a rotary movement to carry said lug thereon through the 5 slots in said hub and nut.

6. A taping head according to claim 2, further including means for holding the tape package against turning in its support, said means including said plates for clamping the sides of 10 said tape-package.

7. A taping head according to claim 1, further comprising guides over which said tape is reeved in running from said package to a cable or the like on which it is wound, one of said guides 15 comprising a crowned part, the center-lines of tapes of different widths running from the package over identical points on the guides and to the apex of the crown of said crowned guide.

HERMAN ZARAFU. 20
